UNITED STATES PATENT OFFICE.

CLINTON B. PIKE, OF BIRMINGHAM, ALABAMA.

VIBRATING APPARATUS AND METHOD FOR ITS UTILIZATION FOR REMOVING PATTERNS AND CASTINGS FROM SAND MOLDS.

Application filed August 8, 1927. Serial No. 211,395.

My invention relates to a novel vibrating apparatus and to a method for its use to facilitate the removal of patterns and castings from sand molds. My invention is especially, though not exclusively, adapted for the removal of patterns used for forming sand molds for hollow cylindrical cast metal bodies such as cast iron pipe and the like, and I contemplate that it will prove efficacious for freeing hollow castings, irrespective of their shape or composition, from the sand mold in which they were cast and thereby facilitating their removal.

As my invention in the form herein shown is more particularly directed to the centrifugal cast pipe art wherein sand molds are employed, its application to that will be more particularly described, without thereby intending to limit my invention to such particular use.

In the present practice of forming centrifugal sand molds for pipe, the sand is rammed either by jolting or the pneumatic methods which result in the packing or compression of the sand by blows or motion in the direction of the long axis of the mold, and while this produces an exceedingly dense mold from which it is very difficult to remove either the pattern or the finished casting, nevertheless I have found that the sand, even though thus densely packed, will readily yield, sufficiently to loosen its grip on the pattern, to forces applied radially or transversely to the long axis of the pipe and it is this slight radial or transverse compressing of the sand which my invention makes use of to free the pattern or casing and permit its ready removal from the mold.

My invention contemplates the utilization of a rapidly rotating vibrator, preferably in the form of a disk or cylindrical body mounted concentrically on its drive shaft, which body is adapted, responsive to centrifugal or gyroscopic forces, to assume a working position more or less out of line with the axis of the hollow body to be vibrated thereby and which is free to have a planetary motion within the vibrated element as it travels, responsive to its rotating drive, in an orbit about the long axis of the hollow body. As the vibrator moves with more or less frictional engagement with the vibrated element it imparts thereto a rhythmical vibrating or oscillatory motion about its own long axis, said motion being in its extent governed by

various factors such as the relative diameters of the vibrator and of the interior of the element vibrated, the R. P. M. of the vibrator head, and its weight relative to the weight or inertia of the element to be vibrated.

By my improved method and apparatus I am able to produce vibrations representing in number multiples of the R. P. M. of the vibrator and these relatively short frequent impulses following the planetary movement of the vibrator tend to move the vibrated body rhythmically about its long axis, and act in a remarkably short time to effect a sufficient radial compression of the sand which will loosen the pattern or casting and facilitate its ready removal. This radial or lateral compression of the sand in the mold needed to free the pattern is very slight and it takes place with maximum uniformity throughout thereby leaving the sand mold not only in ideal condition as to surface compactness and smoothness, but also free of any distortion that may effect the uniform structure of the casting. Obviously it is possible to free the pattern by an infinitely small enlargement of the mold diameter as both sand mold and pattern are inelastic elements and yet an exceedingly small enlargement of the mold makes it possible to free and remove the pattern or finished casting from the mold with remarkable ease. At the present such patterns and casting are removed with the greatest difficulty, both the pattern and the mold being subjected to very great forces in the effort to pull the pattern from the mold and it being usually necessary to cut away the sand from about the casting by augurs, drills and the like.

Some of the more important advantages of my invention over previous practice in the sand molding art are:—That the vibrating element need not be attached to the element vibrated and is thus freely movable into and out of operating relation therewith; it is free to co-act circumferentially within the element vibrated so as to work in all directions radially against the sand; it feeds itself automatically about the interior of the element vibrated and tends to cause a cylindrical element to follow it with a lag when loosened; it is adapted to have ready relative adjustment lengthwise of the element vibrated, if such be necessary, so as to work at different points lengthwise of the elongated vibrated element;

and it is susceptible of wide variation in structure, requiring only a rotating vibrator head suitable to frictionally engage the inner perimeter of the element vibrated and having a flexible drive shaft which will permit it to follow a planetary motion while at work.

With the above objects in view my invention consists in the device and in the process for utilizing it which is hereinafter more particularly described and claimed in typical embodiments thereof, reference being had to the accompanying drawings, in which:—

Fig. 1 shows a vertical section through a sand mold for the casting of centrifugal pipe having therein a hollow pattern with which a single vibrator is shown in co-operative relation.

Fig. 2 shows a modification of my invention, wherein a plurality of vibrators are carried by a flexible sectional shaft and adapted to co-act at a plurality of points lengthwise of the element vibrated to impart synchronous vibrations throughout its length.

Fig. 3 is a plan view of Fig. 1, showing vibrator unbalanced.

Similar reference numerals refer to similar parts throughout the drawings.

In the embodiment of my invention illustrated in Figs. 1 and 2, I show a mold flask 5, suitable for receiving a cylindrical or hollow pattern 6, between which and the flask sand is rammed to form a mold 7 by any suitable mechanism which need not be described. The pattern shown is of a straight cylindrical type for casting a cylindrical body such as a pipe, tube or like hollow casting and therefore serves merely as a conventional illustration typical of any pattern or element to be vibrated. The interior of the pattern will be preferably cylindrical but this is not essential. After such pattern has been set in place and the sand tightly rammed about it, it has proven difficult to remove it from the sand mold and to overcome this I propose to make use of the mechanism which will now be described.

Above the mold I dispose a rotary motor or drive means 8, preferably an electric motor, and in order to produce relative axial movement between the motor and the flask I provide as the simplest means an I-beam guide 9 which is engaged by a slide bracket 10 carrying the motor and supporting the motor with its shaft substantially concentric with the pattern. A shaft 11 driven by the motor is adapted to depend into the pattern and carries fast on its lower end a vibrator head 12, which can be balanced or unbalanced on its shaft. This head can be made up in many ways and will have a diameter less to the desired degree than the diameter of the pattern, and a weight which will be varied in accordance with the duty required. As shown in Fig. 1, the head comprises a metal cylinder 12 mounted concentrically in bal-

anced relation on the shaft 11 between plates 13 which are secured by nuts 14 and overhang the cylinder so as to receive and hold in position between them an annular tread element 15 which can be of any material best suited for the duty contemplated. 70

Preferably, the shaft 11 will provide sufficient flexibility for the head, as it is rapidly rotated, to move laterally until its tread portion engages the inner circumferential wall of the 75 pattern or element to be vibrated. A frictional engagement between the head and pattern will result and will produce a planetary movement of the rotating head as it travels about the pattern. As the head moves it imparts lateral or radial vibrations to the pattern tending to cause the axis of the pattern to move outwardly along a spiral path thereby effecting a slight radial compression of the surrounding sand. The number of rotations of the head in completing its orbit will be determined by the relation of its circumference to the inner perimeter of the pattern or element vibrated and for each rotation of the head there will be obtained a plurality of 80 vibrations dependent on various operating conditions.

By raising the head it can be caused to act on the pattern in various positions lengthwise thereof and as soon as the pattern is loosened at all, if it is cylindrical, 95 it will tend to rotate and follow the head responsive to the frictional engagement therewith of the head, and when freed it can be stripped with ease.

It will be seen that, as the head 12 is rapidly rotated, and is brought into frictional engagement with the wall of the pattern 6, the inner surface of the pattern 6 serves as a track for the rotating head 12. Ordinarily, the head 12 is brought into frictional engagement with the inner surface of the pattern immediately upon starting the motor 8, due to its own centrifugal force. I have found, however, that it is sometimes necessary, in order to secure immediate frictional engagement, to laterally displace the shaft sufficiently for the head to come in contact with the inner surface of the cylinder. Once in contact, the inner surface of the pattern serves as a track or race for the head 12 upon which it runs. As the head 12 runs about the inner surface of the pattern, it exerts a centrifugal force radially against the wall of the pattern which is represented by the following formula:

$$F = \frac{Wv^2}{gR},$$

where W represents the weight of the head in pounds, v the linear velocity of the center of gravity of the head 12 and its connections in feet per second, g the constant 32.174, and R the radius of revolution of the center of gravity in feet. This radially directed centrifugal force serves to symmetrically com- 130

press the sand about the pattern until the pattern is loosened.

In Fig. 2, I show the vibrator head with a hole 23 to unbalance it. Such unbalancing will not change the action above described but will change the character of the vibrations.

In Fig. 3 I have shown a device adapted to simultaneously vibrate a pattern or finished casting at various levels, thus expediting the work of freeing the pattern or casting from the sand mold. Here the motor 8 is supported by a suitable adjustable support 16 and has a shaft 17 connected by a flexible joint 18 to a shaft section 19 carrying a rotating vibrator head 20. In like manner the shaft section 19 is connected by a flexible joint 18 with a shaft section 21 and it in turn by a flexible coupling 18 with a shaft section 22, each shaft section carrying its vibrator 20. This device is lowered into the cylindrical pattern or finished casting and rotated when it will have the planetary movement described, and by engagement with the inner walls with the pattern or casting produce a multiplicity of radially directed vibrations and which will be represented by a high multiple of the rotation of the shaft itself and these will gradually act on the pattern or casting to radially compress the sand mold sufficiently to free the pattern or casting from the sand and permit its ready removal. The effect produced by the rotating traveling head on the pattern or casting may or may not be truly vibratory but certainly it causes such a displacement of the element acted upon in all directions in the plane of the head's rotation that the sand is uniformly compressed on all sides of the said element. The vibrator head shows here a tread 15 of such character that when the head is centrifugally disposed the frictional engagement of the tread 15 with the vibrated element will cause the head to travel about the inner perimeter of the element whatever its shape and as it moves to cause the displacement of the element for the purposes desired. The vibrator must be subjected to centrifugal force to cause it to perform its work, and this can be accomplished by its motion about an axis whether or not it be at the same time rotated about its own axis, and it can be designed as it swings around and frictionally engages the work to impart the desired vibration and motion thereto.

While I have shown my invention in but two forms, it will be obvious to those skilled in the art that it is not so limited, but is susceptible to various other changes and modifications, without departing from the spirit thereof, and I desire, therefore, that only such limitations shall be placed thereupon as are imposed by the prior art or as are specifically set forth in the appended claims.

Having thus described my invention, what

I claim as new and desire to secure by Letters Patent, is:—

1. In an apparatus of the character described, a vibrator, drive means therefor, and a hollow element having its internal perimeter frictionally engaged by the driven vibrator to radially displace it.

2. In an apparatus of the character described, a vibrator, drive means therefor which displace it responsive to centrifugal force, and a hollow element having its internal perimeter frictionally engaged by the driven vibrator to laterally displace said element and to cause progressive movement of the vibrator about the element's perimeter.

3. In an apparatus of the character described, a vibrator, a flexible drive shaft for rotating said vibrator and supporting it free for lateral displacement, and a hollow element to be vibrated having an internal perimeter about which the vibrator progresses responsive to friction and centrifugal force and which tends to be disposed in the direction in which the centrifugal force is exerted thereon.

4. Apparatus according to claim 3, in which the vibrator comprises a plurality of vibrator heads mounted in spaced relation along said drive shaft.

5. In a process for the loosening, free for removal, of patterns, castings and the like from sand molds, the step which consists in subjecting the article to be removed to internal force exerted outwardly and progressively about its internal perimeter.

6. The method of loosening a hollow cylindrical pattern from a sand mold without distortion of the sand which comprises, subjecting the inner surface of the pattern to a relatively high frequency radially directed vibratory force, said force acting circumferentially around the inner surface of the pattern.

7. The method of loosening a hollow cylindrical pattern in a sand mold without distortion of the sand which comprises, subjecting the inner surface of the pattern to a relatively high frequency radially directed vibratory force, said force being distributed circumferentially and longitudinally of the pattern.

8. The method of loosening a cylindrical pattern in a sand mold without distortion of the sand which comprises, symmetrically enlarging the mold around the pattern by a relatively high frequency vibratory force directed radially against the inner surface of the pattern.

9. The method of sand molding, which consists in compacting the sand about a pattern to form the initial mold, then subjecting the pattern to a vibratory action applied substantially uniformly about it thereby to symmetrically enlarge the mold sufficiently to release the pattern for ready removal.

10. In apparatus for loosening a hollow cylindrical pattern from a sand mold, a rotary member loosely fitting within the pattern, a motor for driving the rotary member, and flexible means connecting the motor and rotary member.

11. In apparatus for loosening a hollow cylindrical pattern from a sand mold, a rotary member loosely fitting within the pattern, a motor for driving the rotary member, flexible means connecting the motor and the rotary member, and means providing relative longitudinal movement of the rotary member and the pattern while rotating.

12. In apparatus for loosening a hollow cylindrical pattern from a sand mold, a rotary member within the pattern, a motor having its axis of rotation in axial alignment with the pattern, and flexible driving means connecting the motor and the rotary member. 15

13. In apparatus for loosening hollow cylinders in said molds, a rotary member disposed within the hollow of the cylinder and adapted to track around the inner surface thereof, and means for driving the rotary member. 20

In testimony whereof I affix my signature.

CLINTON B. PIKE.
